UNITED STATES PATENT OFFICE.

OSWALD S. PULLIAM, OF PITTSBURGH, PENNSYLVANIA, ASSIGNOR TO PITTSBURG EQUIPMENT COMPANY, OF PITTSBURGH, PENNSYLVANIA, A CORPORATION OF PENNSYLVANIA.

CAR-TRUCK SIDE FRAME.

1,923,481.

Specification of Letters Patent. Patented Apr. 16, 1912.

Application filed February 23, 1911. Serial No. 610,186.

To all whom it may concern:

Be it known that I, OSWALD S. PULLIAM, of Pittsburgh, in the county of Allegheny and State of Pennsylvania, have invented 5 certain new and useful Improvements in Car-Truck Side Frames, of which the following is a specification.

An object of my invention is to provide 10 a new and improved car truck side frame comprising a top-member, a bottom-member and journal boxes, preferably formed as an integral cast metal structure, having a column or columns connecting the top and bottom members, with said column or 15 columns constructed to permit a bolster having column-guides formed integral therewith, to be readily placed in position in the side-frame and removed therefrom.

Further objects of the present invention 20 are to provide a side frame having a column provided with a separable portion adapted to be removed to permit a bolster to be passed through the column, and to provide means for connecting the separable portion 25 of the column to the side frame.

A still further object of the present invention is to provide a column comprising a separable portion with a brake-beam hanger formed integral therewith.

30 In the accompanying drawing, which illustrates applications of my invention, Figure 1 is a side elevational view of a side frame constructed in accordance with my invention; Fig. 2, a vertical sectional view 35 taken on line II-II of Fig. 1; Fig. 3, a side elevational view of a modified form of my invention showing each of the columns provided with separable portions; Fig. 4, a sectional view taken on line IV-IV of Fig. 40 3; Fig. 5, a side elevational view showing each of the columns provided with a separable portion and a modified form of construction for securing a brake-beam hanger to the side frame; Fig. 6, a vertical sectional 45 view of the form of Fig. 5; Fig. 7, a side elevational view of the side frame constructed in accordance with my invention showing brake-beam hangers formed integral with the removable or separable portions of the columns; Fig. 8, a vertical sectional view particularly showing a brake-beam hanger formed integral with a separable portion of a column; Fig. 9, a side elevational view of a still further modified

form of my invention; and Fig. 10, a detailed sectional view taken on line X-X of Fig. 9.

Referring to the drawing, 1 designates a top-member of a side frame, 2 a bottom-member thereof, and 3 the journal-boxes 60 formed integral with the ends of the top and bottom-members. The side frame as illustrated and as preferred comprises the top-member, bottom-member, and journal-boxes all formed in an integral casting, but 65 the journal-boxes may be separable if desired.

In the form of Fig. 1, I have shown one 70 of the columns 4, connecting the top and bottom-members of the side frame, as a continuous member formed integral with the casting constituting the side frame, while the other column comprises a separable or detachable member 5 and two integral column portions 6 and 6^a respectively 75 formed with the top and bottom-members. The separable member 5 is provided at its upper and lower ends with apertured lugs 7 and is secured to the respective portions 6 and 6^a by bolts 8 adapted to be passed 80 through the apertures in the separable portion of member 5 and corresponding apertures formed in the portions 6 and 6^a respectively.

In all of the modified forms of my invention as illustrated, the separable portions 5, comprising portions of the columns connecting the top and bottom-members of the side frame are similar, with the exception of the form of Fig. 9, which will be 90 hereinafter more fully described. By forming the columns with the separable portions as shown, I am enabled to place a bolster having column-guides formed integral therewith in position in the side frame by simply 95 removing one or both of the separable portions 5.

9 designate brake-beam hangers adapted to be secured to the side frame; and in the form of Fig. 1 the upper or top-member of 100 the side frame is formed with openings 10 adapted to receive a reduced portion 11 of the hanger, said hanger being secured thereto by a nut 12. In the form of Fig. 5, as particularly shown by Fig. 6, I place the 105 brake-beam hanger in a lower position than in the form of Fig. 1 and have its reduced portion 11 passed through the apertures

formed in the lugs of the separable portion 5 and through the opening formed in the respective integral portion 6 and 6^a. In the form of Fig. 7 the brake-beam hanger is 5 formed integral with the separable portion of the column.

Fig. 9 illustrates a modified form of column and separable portion thereof and a different manner of securing the separable 10 portion of the column to the integral portions thereof. In this form, 5^a designates the separable portion of the side frame column, and 6^b and 6^c the integral portions thereof. The separable portion of each 15 column is connected with the integral portions thereof by means of a vertically extending column-bolt 13 adapted to be passed through opening *d* formed in the respective integral column portions and through opening 20 *e* formed in the separable portion 5^a.

What I claim is:

1. A car truck side frame having integral top and bottom members, a column having an opening, said column opening being 25 adapted to permit a bolster to be passed therethrough, and means for closing the opening.
2. A car truck side frame having top and bottom members and a column connecting the top and bottom members, said column having an opening adapted to permit a bolster to be passed therethrough, and means for closing the opening.
3. A car truck side frame comprising a 30 top-member, a bottom-member and a journal-box all formed integral, a portion of a column formed integral with the top-member and a portion formed integral with the bottom-member, and a separable column portion connecting the integral column portions.
4. A car truck side frame having top and

bottom members each formed with a column portion, and a separable column portion connecting the integral column portions.

45

5. A car truck side frame comprising a top-member, a bottom-member and a journal-box all formed integral, a portion of a column formed integral with the top-member and a portion formed integral with the 50 bottom-member, a separable column portion connecting the integral column portions, and means for securing the separable portion to the integral portions.

6. A car truck side frame having top and bottom members each formed with a column portion, a separable column portion connecting the integral column portions, and means for securing the separable column portion to the integral column portions.

60

7. A car truck side frame having integral top and bottom members, a column having an opening, said column opening being adapted to permit a bolster to be passed therethrough, and closing means for the opening having a brake-beam hanger formed integral therewith.

65

8. A car truck side frame having top and bottom members each formed with a column portion, and a separable column portion formed with a brake-beam hanger connecting the integral column portions.

70

9. A car truck side frame comprising a top-member, a bottom-member, a column connecting the top and bottom members comprising a portion formed integral with the top and bottom members and a separable portion connecting the integral portions.

75

In testimony whereof I affix my signature in presence of two witnesses.

OSWALD S. PULLIAM.
